STEAM-TURBINE PLANT FOR HIGH PRESSURES AND VERY HIGH SUPERHEATING

Application filed July 8, 1922, Serial No. 573,731, and in Switzerland May 13, 1922.

This invention relates to steam plant installations, and pertains particularly to installations in which it may be desired to employ highly superheated steam.

5 The general object of the invention is the provision of an installation which will possess good efficiency not only at normal loads but also at abnormal and subnormal loads.

Another object is the provision of an installation particularly qualified for the utilization of highly superheated steam.

A further object is the provision of an installation which permits the use of highly superheated steam or of lower temperature steam selectively, for different load requirements, with efficient performance, and without subjection of the control gear or of the parts designed for use of the lower temperature steam to the possibly injurious effects of 20 the highly superheated steam.

Other and further objects will be pointed out or indicated hereinafter or will be apparent to one skilled in the art upon an understanding of the invention or its employment in practice.

In the accompanying drawings forming a part of this specification, we show in diagrammatic fashion certain arrangements of apparatus representative of embodiments of 30 the invention, but it is to be understood that these are presented for purpose of illustration only and are not to be accorded any interpretation calculated to limit the claims short of the true and most comprehensive scope of 35 the invention in the art.

In the drawings,

Fig. 1 is a diagrammatic or schematic illustration of an installation including a turbine designed for operation by highly superheated 40 steam and an associated turbine designed for operation with lower temperature steam, together with their control gear for governing the supply of steam to them;

Fig. 2 is a diagrammatic illustration of 45 regulating gear as applied to the steam regulating valves ahead of the superheater;

Fig. 3 is a diagrammatic illustration of 50 regulating gear for controlling the steam supply to the low pressure turbine and illustrates also a modification of part of the regu-

lating gear for limiting pressure in the supply line; and

Fig. 4 is a detail in the nature of a cross section through one of the regulating devices, the section being taken on line 4-4 of Fig. 2. 55

It is recognized that certain improvements in efficiency in some steam turbine installations may be obtained by use of high steam pressure derived from high superheating. The use of highly superheated steam requires, however, certain special characteristics in the construction of the turbine which are not required in turbines constructed for use of lower temperature steam. Likewise, the control of the steam supply to the high pressure turbine, when highly superheated steam is employed, involves certain considerations which do not arise in the handling of lower temperature steam, said considerations having to do principally with the safe- 60

guarding of the control gear from the pronounced thermal effects of the highly superheated steam. The present invention provides an installation which facilitates working with highly superheated steam and con- 65

tributes to the safety and the efficiency of the installation. Described generally, one form of installation contemplated by the present invention includes a high pressure turbine especially qualified for working with highly 70 superheated steam, a low pressure turbine arranged to be worked with either or both the exhaust steam from the high pressure turbine and steam from the supply line, a superheater for superheating steam from the 75 supply line for the high pressure turbine, control gear between the superheater and the supply line for controlling the steam supply to the high pressure turbine, together with appropriate regulating and control gear for 80 governing steam supply to the low pressure turbine and to the low and high pressure turbines conjointly.

For a more detailed understanding of the invention, reference is had to the assembly 95 illustrated in the drawings, wherein the reference character *a* designates a high pressure turbine qualified for operation by highly superheated steam, and *b* a low pressure turbine. It will be understood in refer- 100

ring to these turbines as the high pressure and low pressure turbines, those terms are employed for the purpose of designation only, because, while the invention contemplates that the high pressure turbine is properly qualified for operation by highly superheated steam, the low pressure turbine may be of normal design suitable for using normal pressure steam or steam of normal superheats. The reference character *c* designates a steam supply line which may be supplied with steam at boiler pressure or at normal superheats. Between the supply line and the high pressure turbine is interposed a superheater or superheaters, designated *d*¹, *d*², *d*³ and *d*⁴, wherein the steam is highly superheated, and from which it is led to the high pressure turbine through the pipes *e*¹, *e*², *e*³ and *e*⁴ to supply the nozzle ring or rings *f*. On its exhaust side, the high pressure turbine is connected to the steam inlets of the low pressure turbine by a pipe *g*, which is controlled by a valve *x*, and a branch pipe *h* affords a second supply connection for the low pressure turbine, from the supply line *c*. The steam regulating valves for the high pressure turbine are interposed between the supply line *c* and the superheaters *d*¹, *d*², *d*³ and *d*⁴, said regulating valves being designated *n*¹, *n*², *n*³, and *n*⁴, and a regulating valve *o* is arranged in the branch line *h* for controlling supply of steam from the line *c* directly to the low pressure turbine. These regulating valves as herein illustrated are of the type operated by a servo system, as exemplified in British Patent No. 3,893/1914, being operated by oil supplied under pressure in the servo lines *m*, *m*¹ and *p*, wherein the effective pressure is regulated by governors *i* and *i*¹ operated by the turbines. The principle of operation of such regulating gear may be ascertained more clearly by reference to Figs. 2 and 3. Referring to Fig. 2, it will be understood that oil under pressure is supplied from a servo pump *l*¹ (Fig. 1) to line *m* which leads it to the regulator cylinders under the pistons *q*¹, wherein it is effective in opposition to the influence of the springs *r*¹ to determine the vertical position of the pistons. The pistons *q*¹ are connected to the valves *n*¹ and *n*², and in accordance with their positions, govern the passage of steam through the valves from the supply line *c*. The effective pressure of the oil in line *m* is determined by the position of the valve sleeve *k*¹ of the governor *i*¹, which valve sleeve assumes different positions in accordance with the speed of the governor to vary the effective size of its lateral discharge aperture and in that manner vary the leakage of oil from the servo line to regulate the pressure effective under the pistons *q*¹. Thus, the regulating valves *n*¹, *n*², *n*³ and *n*⁴ are governed from the high pressure turbine, while regulating valve *o* is governed in simi-

lar manner from the low pressure turbine through the instrumentality of the governor *i*, servo pump *l* and pressure regulator *k*. The valve *o* may also be controlled by the governor *i*¹ by way of servo lines *m* and *p*, as illustrated in Fig. 1. Valve *o* may be cut off from control by regulator *i*¹ by the closing of valve *y* in the servo line. The high pressure turbine may be cut out completely by closing the valve *v* in the supply line and the valve *x* between the low and high pressure turbines. The arrangement of the governing gear is such that, through the regulating instrumentalities above described, a decrease in the speed of either turbine results in an increase of the oil pressure under the valve regulating pistons, causing the pistons to be lifted and their valves to be given an opening movement to increase the steam admission to the superheaters, in the case of the valves *n*¹, *n*², *n*³ and *n*⁴, or to the low pressure turbine, in the case of the valve *o*. In this connection, the springs *r*¹ are selected and adjusted in the same manner and for the same purpose as is customary with the type of governing gear illustrated, that is, the spring associated with valve *n*¹ is under the least compressive stress so that valve *n*¹ opens first under a given pressure condition in the oil line, while the spring associated with valve *n*² is under greater compressive stress so that valve *n*² opens after opening operation of valve *n*¹ and upon corresponding increase in the pressure condition in the oil line, and so on, opening operation of valves *n*³, *n*⁴ and *o* following in the order named and upon still further increase in pressure conditions in the oil line by corresponding increments. At maximum load, therefore, whereat the oil pressure is greatest, all of the valves will be open. An increase in speed of the governor results in decrease of the oil pressure and a corresponding reverse operation of the valves concerned. In operation at normal load on the turbines, steam from the supply line *c* is supplied to the superheaters *d*¹, *d*², *d*³, and *d*⁴ in accordance with the load requirements, under regulation of valves *n*¹, *n*², *n*³ and *n*⁴. In the superheaters this steam is highly superheated, and from them is delivered to the high pressure turbine, in which it is expanded back to a normal pressure suitable for use in a low pressure turbine, to which it is led through the connection *g*. At overloads, live steam may be admitted from supply line *c* to the low pressure turbine by way of branch pipe *h*, by the regulating operation of valve *o* in response to a speed drop of either or both of the turbines, valve *o* throttling the pressure of this directly supplied steam to a pressure equal to that prevailing in the series connection *g*, in the event the line pressure exceeds same. At subnormal load, the high pressure turbine may be cut out completely

by closing valves v and x , upon which contingency servo valve y is also closed, so that the regulation of valve o is entirely from the governor of the low pressure turbine.

Many advantages are attained in an installation of the sort described. In the first place, the high pressure turbine being independent of the structural limitations of the low pressure turbine, it may embody the special structural features which enable it to meet the requirements exacted by the high temperature and pressure of the highly superheated steam, and it may be constructed with small wheel diameters, to admit of rapid revolution without excessive wheel velocities. Accordingly, it may be built as a relatively small but efficient unit and at an economical cost. In the second place, the control gear, such as the valves for controlling the steam supply to the high pressure turbine, may be of normal construction, because they are not subjected to the extreme temperatures of the highly superheated steam. Thus, while, by virtue of the manner in which the installation is organized, the regulating gear is qualified to regulate effectively the supply of highly superheated steam to the high pressure turbine, as well as lower temperature steam to the low pressure turbine, it is safeguarded against high temperature effects and possesses the combined advantages of economy in cost and reliability in operation. Another important advantage in the direction of overall efficiency and reliability of the installation resides in the permissible latitude in distribution of load between the two turbines. If it is assumed, for instance, that the highest admissible superheating be 460° to 500° C., and that the steam be expanded in the high pressure or primary unit to 300° or 350° C., which temperature can be considered as normal for the present practice and harmless for the materials and type of construction used in the low pressure turbine, the turbines may be designed so that the low pressure unit can take a load of from two to three times that of the high pressure unit. The low pressure unit, therefore, can be qualified to deliver from two-thirds to three-fourths of the whole output of the installation. Consequently, even in event that it may be necessary to cut out the high pressure unit for repair or from other abnormal circumstance, the installation can be operated with the low pressure unit alone to supply the greater portion of the demand on the plant. Thus, while the plant is qualified to avail of the advantages to be derived from the use of highly superheated steam for normal operation, it can have a capacity for assuming a substantial overload demand and also for supplying the greater proportion of the normal demand even in the event of disablement of the high pressure unit. In the event of the last mentioned contingency, the output of

the low pressure unit may be increased by an increase of the line pressure above its normal, which may be done economically due to the fact that the superheaters for the high pressure turbine would be cut out at such time, and the heat sources normally devoted to them may be diverted to increasing the line pressure. For the purpose of preventing such over-regulation of valve o as to cause too great a load to be taken over by the low pressure turbine when working on an alternating current system, or such that the turbine is endangered by too high pressure, a limiting arrangement for valve o should be provided. One such arrangement is illustrated in detail in Fig. 3, and includes a limit valve t' which, by opening, reduces pressure in the servo line serving the governing gear q of valve o . Limit valve t' is controlled individually by a regulator t which is responsive to pressure conditions in line h so that, when the pressure in line h reaches the maximum for which the regulator t is set, limit valve t' will be opened and further opening of valve o by its regulating gear q fore stalled.

It is contemplated that the output of both turbines is directed to a common end, such as the generation of electric power for a system. Consequently, the turbines may be arranged to drive respective generators which supply the system jointly, or they may be connected to the same generator by suitable gearing arrangement. It will be understood also that the steam connections between the turbines may be variously arranged to attain the necessary result of utilizing the heat drop of the highly superheated steam in the high pressure turbine to an extent effective to expand the steam to a temperature suitable for employment in the low pressure turbine without subjecting the latter to conditions of temperature and pressure which require the special structural features that characterize the high pressure turbine. Yet another advantage of the invention resides in the fact that it can be applied to existing installations by the addition of the high temperature turbine for operation in conjunction with a normal pressure turbine already installed, and the addition of such boiler and superheater equipment as may be necessary. In this way, an uneconomical plant may be converted into an economical one without exchanging the more expensive portions of the installation.

What we claim is:

1. In a steam plant installation, in combination, a high pressure turbine, a lower pressure turbine, a steam supply, a superheater connected between the steam supply and the high pressure turbine, a connection between said turbines for supplying the lower pressure turbine with working steam expanded in the high pressure turbine, a valve connected between the steam supply and superheater

- for controlling steam supply to the high pressure turbine by way of the latter, and governing gear for said valve responsive to operation of either of the turbines.
2. In a steam plant installation, in combination, a high pressure turbine, a lower pressure turbine, a steam supply, a superheater connected between the steam supply and high pressure turbine, a connection between said turbines for supplying the lower pressure turbine with working steam expanded in the high pressure turbine, a supply connection between the lower pressure turbine and steam supply for supplying the former with working steam, valves between the steam supply and superheater and in said supply connection for controlling steam supply to the turbines, and governing gear for said valves responsive to operation of either of said turbines.
3. A combination as specified in claim 2, wherein the governing gear operates to open the valve in said supply connection under conditions of overload on the turbines.
4. In a steam plant installation, in combination, a high pressure turbine, a lower pressure turbine, a steam supply, a superheater connected between the steam supply and high pressure turbine, a connection between said turbines for supplying the lower pressure turbine with working steam expanded in the high pressure turbine, a supply connection between the lower pressure turbine and steam supply for supplying the former with working steam, valves in said supply connection and between the steam supply and superheater for controlling supply of steam to said turbines and governing gear responsive to operation of either of said turbines for controlling said valves.
5. In a steam plant installation, in combination, a high pressure turbine constructed for operation by highly superheated steam, a lower pressure turbine constructed for operation by normal pressure steam, a steam supply, a superheater connected between the steam supply and high pressure turbine, a connection between said turbines for supplying the lower pressure turbine with working steam expanded in the high pressure turbine, a valve connected between the steam supply and superheater for controlling supply of steam to the high pressure turbine, and governing gear responsive to operation of either of said turbines for controlling said valve.
6. A combination as specified in claim 5, in which the lower pressure turbine is adapted to carry the major proportion of the aggregate output load of the two turbines.
7. A combination as specified in claim 2, together with automatic means for limiting the maximum steam admission through the valve in said supply connection.
8. In a steam plant installation, in combination, a high pressure turbine, a lower pressure turbine, a steam supply, a superheater connected between the steam supply and high pressure turbine, a connection between said turbines for supplying the lower pressure turbine with working steam expanded in the high pressure turbine, a supply connection between the lower pressure turbine and steam supply for supplying the former with working steam, a valve connected between the steam supply and superheater for controlling supply of steam to the high pressure turbine, a second valve for controlling steam admission to the lower pressure turbine from said supply connection, governing gear responsive to operation of the lower pressure turbine for controlling said second valve, and governing gear responsive to operation of the high pressure turbine for controlling both said valves.
- In testimony whereof we have signed our names to this specification.
- W. G. NOACK.
A. MEYER.
